UNITED STATES PATENT OFFICE.

JOHN HOWE, OF AURORA, ILLINOIS.

BELL-RINGER FOR LOCOMOTIVES.

1,231,357.

Specification of Letters Patent. Patented June 26, 1917.

Application filed March 8, 1915. Serial No. 13,058.

To all whom it may concern:

Be it known that I, JOHN HOWE, a citizen of the United States, residing at Aurora, in the county of Kane and State of Illinois, have invented certain new and useful Improvements in Bell-Ringers for Locomotives, of which the following is a specification.

This invention relates to bell ringers of a type adapted for use in ringing the bell of a locomotive. More particularly the invention relates to improvements in means for controlling the movements of a bell.

Great difficulty is experienced with present bell ringers, owing to the tendency of the bell to turn completely over after being actuated in a given angular direction, which action interferes with the successful operation of the bell and the regularity of the sounds emitted thereby. When the compressed fluid which actuates the bell-ringing mechanism is admitted thereto in such limited degree as to prevent the bell from turning over, it is found that the pressure is generally not sufficient to start the bell from rest, and some supplementary means, such as a bell rope, must be employed for that purpose.

It is the purpose of the present invention to overcome the above difficulties and many others, and my principal object is to provide improved means for preventing the bell from turning completely over after it has been actuated. A further object is to provide a fluid-actuated bell ringer to which the compressed fluid may be admitted in any desired degree sufficiently to readily start the bell from rest and actuate the same, without danger of the bell turning over. Another object is to provide means for actuating the bell and then bringing the bell to rest after it has passed through the desired arc of movement. Still another object is to provide a bell ringer actuated by compressed fluid which will operate automatically to ring the bell continuously without turning over, while the supply of compressed fluid is admitted thereto. The mechanism which retards the upward movement of the bell, also acts to retard the downward movement of the return stroke.

These and other objects of the invention will be set forth more particularly in the following specification, taken with the accompanying drawings in which one embodiment of the invention is illustrated.

In the drawings,—

Figure 1 is an elevation of a bell and bell frame with my improved bell ringer in operative relation thereto, the bell being shown in normal inoperative position;

Fig. 2 is a sectional view taken on the line 2—2 of Fig. 1;

Fig. 3 is a vertical sectional view through the bell ringer, taken parallel to the view shown in Fig. 1, certain elements being shown in elevation, the position of the bell crank and operating mechanism corresponding to the position shown in Fig. 1;

Fig. 4 is an elevation of the upper portion of the bell ringing mechanism, taken at right angles to the view shown in Fig. 1, showing the angular position of the bell crank when the bell is in normal position at rest;

Fig. 5 shows a perspective view of the sliding block or wedge;

Fig. 6 shows a perspective view of a cap which is adapted to coact with the wedge member shown in Fig. 5;

Fig. 7 is an elevation of the bell ringer, being an enlargement of the view shown in Fig. 1, with the bell-actuating mechanism in a position corresponding to one upper limiting position of the bell in its angular movement; and

Fig. 8 is an elevational view taken at right angles to that shown in Fig. 7, with the lower portion thereof in section.

Referring to the drawings: The usual bell frame 10 is shown mounted on top of a locomotive or other support 11, and the arms of said bell frame are provided with alining journal bearings 12 and 13, in which are journaled the bearings 14 and 15, respectively, of the bell yoke 16. The yoke 16 is of the usual form, comprising a U-shaped portion, extending transversely to the axis of the bearings 14 and 15, to the middle portion of which the bell 17 is rigidly connected. As will be well understood by those skilled in the art, the bell yoke 16 and bell 17 are so supported and arranged that the bell normally occupies a position in a vertical plane as shown in Fig. 1, and automatically returns to said position by virtue of its weight. The bell tongue 18 is pivotally mounted in the bell on an axis parallel to the axis of the bearings 14 and 15, so that when the bell yoke is rotated in its bearings in either direction, said tongue will strike the bell and sound the same. A

shaft 19 is formed integrally with the bearing 14 and extends outwardly therefrom, having rigidly secured to the end thereof a bell crank lever 20, which is provided with 5 a threaded aperture 21, adapted to be engaged by a set screw for forming said rigid connection. The other extremity of the bell crank lever 20 is operatively connected to my improved bell ringer in the manner hereinafter described.

Secured to the arm of the bell frame, beneath the bell crank lever 20, is a bracket 25 having an arc-shaped portion 26, which conforms to the arm of the bell frame and is 15 secured thereto by means of the bolt 27 and the stud 28. The bracket 25 is also provided with a downwardly extending flange 29, which is rigidly connected to the cylinder 30 by means of a stud 31. A piston 32 is 20 reciprocally mounted in the chamber 33 of the cylinder 30, and said chamber is enlarged at its lower extremity 35 to prevent the formation of shoulders on the walls of the chamber at the lower limit of movement 25 of the piston 32. The piston 32 is provided with the usual piston ring 36 and the lower end of said piston is provided with a central, downwardly-extending projection 37, which is adapted to engage the upper extremity of 30 the valve stem 38, which is reciprocally mounted in the lower end of the cylinder 30, and which controls the valve 39 mounted in the chamber 40 of the cap 41, which threadedly engages the lower end of the cylinder. 35 The valve stem 38 has the opposite sides thereof milled off, so as to provide apertures 42 which form a communication between the chamber 40 and the chamber 33 of the cylinder when the valve 39 is in the position 40 shown, for instance, in Fig. 3. A duct 43 communicates with the chamber 40 and the lower walls of said duct are threaded to be engaged by a pipe 44, which communicates with the compressed fluid supply, such as a compressed air tank of the air brake system, 45 and the pipe 44 is provided with a valve 45 by means of which the admission of compressed fluid to the cylinder 30 is controlled.

It will be apparent that when the valve 45 is opened to admit compressed fluid to the chamber 40, the valve 39 being in its open position corresponding to the lowermost position of the piston 32, as shown in Fig. 3, said compressed fluid will pass upwardly 50 through the apertures 42 into the enlarged portion 35 of the chamber 33, and thereby operate to drive the piston 32 upwardly in the cylinder 30. During the first portion of this upward movement of the piston 32, 55 the pressure of the compressed fluid on the upper and lower sides of the valve and valve stem will be substantially equal, so that said valve will remain in the position shown in Fig. 3 until the lower extremity of the piston 32 has passed the port 46 which I pro-

vide in the cylinder wall, and which communicates with the atmosphere. When the piston passes the port 46 so as to provide a communication between the chamber 33 and the atmosphere, the pressure upon the upper and lower sides of the valve and valve stem will no longer be equal and said valve will move upwardly to close the apertures 42, whereupon the pressure upon the lower face of the piston will cease. I employ the 75 piston 32 for actuating the bell crank 20 in a manner hereinafter to be described.

Formed integrally with the upper portion of the cylinder 30 are two oppositely-directed flanges 50, which are adapted to 80 be secured to corresponding flanges 51 of a guide member 52 by means of bolts 53 and nuts 54. The guide member 52 extends vertically upward in alignment with the piston 32, and is provided with a vertically-extending 85 groove or slot 55 which serves as a guide-way for the sliding block or wedge member 56, which has an inclined wedging surface 57 formed thereon. The wall of the guide member 52 is provided with a vertically-extending slot 58, which is adapted to be engaged by the connecting rod pin 59. The pin 59 extends through said slot and its inner threaded extremity engages the threaded aperture 60 in the wedge member 56, thereby 90 forming a rigid connection therewith. A washer 61 is mounted on the pin 59 and is adapted to slide upon the plane surface 62, which is formed on the guide member around the slot 58. The pin 59 also has rotatably mounted thereon the connecting rod 63, which is retained in position on said pin, adjacent the washer 61, by the nut 64 and cotter-pin 65. The connecting rod 63 is formed in two parts, 63^a and 63^b, the adjacent extremities of which are oppositely threaded for engagement with a turn-buckle 66 by means of which the effective length of the connecting rod may be adjusted. The turn-buckle 66 may be retained in adjusted 100 position by lock nuts 67. The upper extremity of the connecting rod 63 is provided with a hub portion 68, which is centrally apertured and rotatably mounted on a bolt or pin 69, which engages the lower extremity 115 of the bell crank lever 20. The bolt or pin 69 is provided intermediate its extremities with a fixed collar 70, which abuts against the adjacent portion of the crank arm 20, and a nut 71 engages said pin at the other 120 side of said crank arm. The connecting rod 63 is retained on the pin 69 by means of a washer 72, and a pin 73.

The upper extremity of the piston 32 is provided with a central, circular depression 125 34, which is adapted to receive a substantially semicircular projection 75 formed on the lower end of the wedge member 56 when said piston and said wedge member are in their lowermost positions. It will be ap- 130

parent from the preceding description that when the piston 32 is actuated to move upwardly in the manner previously described, the wedge member 56 will be projected upwardly in its guide and thereby operate the crank arm 63 to rotate the bell crank 20 and thereby actuate the bell. The lower wall 76 of the slot 58 is so arranged as to act as a stop to limit the upward movement 5 of the piston 32 and prevent the same from being projected from the chamber 33 by virtue of its velocity. The port 46 in the cylinder wall should be so located that the lower extremity of the piston 32 will pass 10 and open it before the upper extremity of the piston engages the stop 76. It will be seen, however, that the sliding member 56 is entirely disconnected from the piston 32, and after said piston has come to rest 15 against the stop 76, the sliding block or wedge 56 will continue its upward movement and carry the bell crank 20 and the bell 17 through the desired arc of movement. When the bell ringer is in its normal 20 position in a vertical plane at rest, the bell crank 20 should be slightly off-center, as shown in Fig. 4, so that when the piston 32 is actuated to move upwardly the sliding wedge member 56 and the bell crank 25 30 will start freely from rest.

For the purpose of limiting the upward movement of the sliding wedge member 56 and bringing the bell to rest after it has passed through the desired arc of movement, 35 I provide the upper part of the guide member 52 with two transversely-extending parallel studs or pins 80, upon which is slidably mounted the cap member or brake shoe 81. The cap 81 is provided with two 40 supporting flanges 82, which are adapted to rest upon the walls of the guide member 52 at each edge of the guideway 55, as shown in Fig. 2, and said cap is further provided with two laterally-extending 45 flanges 83 which are apertured at 84 for engagement with the pins 80. The outer extremities of the apertures 84 are enlarged, as shown at 85, and coil springs 86 seat therein upon the pins 80 and abut at their 50 opposite ends against the nuts 87, which threadedly engage the pins 80 and are prevented from disengagement therefrom by pins 88. The guide member 52 is provided at each side of the guideway 55 with upper 55 and lower outwardly-projecting flanges 90 and 91, respectively, which bear against the lateral sides of the cap 81 to prevent lateral displacement thereof, and which also serve as guideways for the projecting flanges 83, 60 so as to support the cap 81 for movement with respect to the guide member 52 against the compression of the springs 86. It will be seen that the flanges 82 are so related to the body portion of the cap member as to 65 provide an inclined, wedging surface 92,

which is adapted to coact with the similarly inclined wedging surface 57 formed on the wedge member 56, when said wedge member passes upwardly in the guideway 55. The lower lugs 91 of the guide member have 70 secured thereto the links 95, which extend transversely therefrom and are secured to the portion 26 of the bracket 25, thereby firmly supporting the guide member and the parts carried thereby with respect to 75 the bell frame.

When the parts of the bell operating mechanism are in normal inoperative position, as shown in Fig. 3, for example, the wedge member 56 is displaced slightly from 80 the brake shoe or cap 81, so that when the compressed fluid is admitted to the chamber 33 to actuate the piston, the wedge member 56 may start freely from rest and move upwardly a short distance before it engages 85 the brake shoe 81. As the upward movement continues, the wedging surface 57 will coact with the wedging surface 92 on the brake shoe and force the brake shoe outwardly against the compression of the 90 springs 86 until the friction created by such action is sufficient to overcome the momentum of the moving parts, whereupon the bell crank 20 and the bell 17 will be brought to rest and the bell will be prevented from 95 turning over or passing to an inverted position. After coming to rest, the weight of the bell, acting through the lever arm between its center of gravity and the axes of the bearings 14 and 15, will be sufficient to 100 disengage the wedge member 56 from the brake shoe 81 and return the wedge member and bell in a reverse movement toward their normal inoperative positions.

In the operation of the device the engineer 105 or other person operates the valve 45 to admit the compressed fluid to the chamber 40, whereupon the compressed fluid will pass upwardly through the apertures 42 around the valve stem into the enlarged portion 35 110 of the chamber 33, and actuate the piston 32 in an upward movement in the cylinder. The upper extremity of the piston being in engagement with the projecting lug 75 formed on the wedge member, said piston 115 will actuate said wedge member and drive the same upwardly in the guideway 55. When the lower end of the piston passes the port 36, the pressure of the compressed fluid upon the upper side of the valve 39 and the 120 valve stem 38 will no longer be equal to the pressure upon the lower sides thereof, because of the escape of the compressed fluid to the atmosphere, and thereupon the valve 39 will close the apertures 42, and the pressure upon the piston 32 will cease. If the momentum of the piston 32 is not otherwise overcome, said piston will be brought to rest upon engaging the stop 76, and will thus 125 be prevented from being projected from the 130

chamber 33. The sliding block 56 is, however, free to move away from the piston and the relatively large momentum imparted to said sliding block during the upward movement of the piston, will be sufficient to carry said block and the parts actuated thereby beyond the position which they occupy when the piston comes to rest, so that said block will continue its upward movement and rotate the bell 17 through the desired arc of movement to sound the same. As the wedge member 56 moves upwardly, it will engage the brake shoe 81, and the pressure of said brake shoe upon the said member will increase as the wedge member continues its movement until finally the wedge member and the bell actuated thereby will be brought to rest. It will be apparent that the nuts 87 may be adjusted on the pins 80, in order to provide a degree of pressure on the brake shoe 81 which will bring the wedge member 56 and the bell 17 to rest at the desired point. After the bell has been brought to rest, its weight will be sufficient to return the wedge member and parts actuated thereby toward the normal position illustrated in Fig. 3, until finally as the bell crank 20 is swinging through the vertical plane, the wedge member 56 will have driven the piston 32 to such position that the valve 39 will be again opened by the engagement of the projection 37 with the upper extremity of the valve stem 38. The compressed fluid will be again admitted to the chamber 33 and will again actuate the piston 32 in an upward direction, but the momentum of the bell in its downward swing will have carried the bell crank 20 beyond the head center position to a point on the opposite side thereof from that which it occupied in the beginning of the previous stroke, so that as the piston 32 moves upwardly, the bell crank 20 will be actuated to rotate the bell in the opposite direction of rotation until it is again brought to rest by the action of the brake shoe 81. In this manner the bell is automatically actuated to rotate alternately in opposite directions without further attention on the part of the engineer or other attendant.

If the valve 39 does not open promptly when the bell is passing through its lowermost position, the connecting rod 63 may be adjusted by means of the turn-buckle 66 so that the wedge member 56 and piston 32 will be driven downwardly the proper distance to sufficiently open the valve 39. It will, of course, be apparent that the piston 32 may return by gravity before being projected downwardly upon the reverse stroke of the wedge member 56, but the weight of said piston alone is not sufficient to open the valve 39 against the pressure of the compressed fluid in the chamber 40 and said valve will not open until actuated by the wedge member 56, which is actuated in its return stroke

by the weight of the bell. It will also be apparent that my improved bell ringer will automatically start the bell from rest and continue the operation of same without any precise adjustment of the valve 45 in admitting the compressed fluid to the apparatus, or without the use of any supplementary means to start the bell from rest.

Although I have shown and described a particular form of my apparatus, it will be understood that it may be embodied in various other forms, and that I contemplate various changes and arrangements of parts without departing from the scope of the invention as defined in the appended claims.

I claim:—

1. In a device of the class described, a bell pivoted on a horizontal axis, a movable part actuated when said bell is operated, and a member frictionally engaging said movable part for limiting the angular movement of said bell.

2. In a device of the class described, a bell frame, a bell rotatively suspended in said frame, means for ringing said bell, and a friction brake operative after a predetermined movement of said bell to cushion said bell and limit the angular movement thereof.

3. In a device of the class described, a pivotally mounted bell, a movable member movable with said bell, a brake shoe adapted to engage automatically said movable member, and means for varying the pressure of said brake shoe on said movable member.

4. In a device of the class described, a bell frame, a bell rotatably suspended in said bell frame, means for ringing said bell, and a friction brake comprising co-acting wedging surfaces for preventing said bell from swinging over and above its axis.

5. In a device of the class described, a rotatably mounted bell, means for ringing said bell comprising a sliding block, means operatively connecting said sliding block with said bell to rotate the same, said sliding block having a wedging surface formed thereon, and means coacting with said wedging surface to bring said block to rest.

6. In a device of the class described, a rotatably mounted bell, means for ringing said bell comprising a sliding block, means operatively connecting said sliding block with said bell to rotate the same, and a brake to limit the movement of said sliding block and to limit the angular movement of said bell.

7. In a device of the class described, a rotatably mounted bell, means for ringing said bell comprising a sliding block, a guide for said sliding block, means operatively connecting said sliding block with said bell to rotate the same, said sliding block having a wedging surface formed thereon, and a plate resiliently mounted on said guide to coact with the said wedging surface.

8. In a device of the class described, a frame, a bell rotatively suspended in said frame, means to impart a rotative impulse to said bell, a movable part actuated by said bell ringing means, and a resiliently mounted brake shoe located in the path of and arranged to grip said movable part to limit the movement thereof. 5
9. In a device of the class described, a rotatively mounted bell, means for intermittently imparting a rotative impulse to said bell, said means comprising a sliding block, and a brake shoe adapted to engage and retard said sliding block to limit the movement of said block and said bell. 10
10. In a device of the class described, an angularly movable bell, a movable member actuated upon movement of said bell, a brake shoe adapted to engage frictionally 15
- 20 said movable member, resilient means arranged to effect an increasing resistance of said brake shoe to the movement of said movable part, and means to vary the effect of said resilient means.
- 25 11. In a device of the class described, a pivotally mounted bell, means to ring said bell, a movable part actuated by the operation of said ringing means, a brake member adapted to frictionally engage said movable 30 part to bring said bell to rest, and means to adjust the pressure of said brake member.
12. In a device of the class described, bell ringing means comprising a slidably mounted member, guides for said member, a brake 35 shoe supported by said guides and adapted to engage frictionally said slidable member, transversely extending members upon which said brake shoe is slidably mounted, and resilient means coöperating with said last 40 named members to press said brake shoe toward said slidable member.
13. In a device of the class described, a bell frame, a bell rotatively suspended in said frame, a bracket attached to said frame, bell ringing means supported by said 45 bracket, said bell ringing means comprising a movable member and a guide for said member, said member having an inclined wedging surface, and a resiliently mounted 50 member having a similarly inclined surface adapted to engage said wedging surface after a predetermined movement of said movable member.
14. In a device of the class described, a pivotally mounted bell, a movable part actuated upon movement of said bell, and a braking means comprising parts adapted to grip said movable part and thereby offer an increasing resistance to the continued movement of said bell after a predetermined angular movement thereof. 55
15. In a device of the class described, a bell frame, a bell rotatively suspended in said frame, a crank for actuating said bell, a slidably mounted member, a connecting 60 rod pivotally connected to said slidably mounted member and to said crank, a resiliently mounted member adapted to engage and limit the movement of said movable member, and actuating means adapted 65 to intermittently engage said slidably mounted member.
16. In combination with a rotatably mounted bell, a sliding block operatively connected with said bell and actuated when 70 said bell is rotated, said sliding block having a wedging surface formed thereon, and means coacting with said wedging surface to bring said block to rest and thereby limit the movement of said bell. 75
17. In combination with a rotatably mounted bell, a sliding block operatively connected to said bell and actuated when said bell is rotated, a guide for said sliding block, said sliding block having a gripping 80 surface formed thereon, and a plate resiliently mounted on said guide to coact with said gripping surface. 85
18. In combination with a pivotally mounted bell, a slidably mounted member 90 operatively connected to said bell to move when said bell is actuated, guides for said member, a brake shoe supported by said guides and adapted to engage frictionally said slidable member, transversely extending 95 members upon which said brake shoe is slidably mounted, and resilient means coöperating with said last-named members to press said brake shoe toward said slidable member.

In testimony whereof, I have subscribed 100
my name.

JOHN HOWE.
